UNITED STATES PATENT OFFICE.

PHILLIP HIEN, OF CHICAGO, ILLINOIS.

DESIGN FOR A CAM-BLOCK FOR CAR-COUPINGS.

SPECIFICATION forming part of Design No. 33,753, dated December 18, 1900.

Application filed November 24, 1900. Serial No. 37,683. Term of patent 14 years.

To all whom it may concern:

Be it known that I, PHILLIP HIEN, a citizen of the United States, and a resident of Chicago, in the county of Cook and State of Illinois, have invented and produced a new and original Design for a Cam-Block for Car-Couplers, of which the following is a specification, reference being had to the accompanying drawings, and to the letters of reference 5 marked thereon, which form a part thereof.

In said drawings, Figure 1 is a perspective view showing the cam-block in side elevation. Fig. 2 is a view taken in the direction of arrow 2 on Fig. 1, showing the cam-block turned 15 on one side. Fig. 3 is a similar view taken in the direction of arrow 3 on Fig. 1. Fig. 4 is a view showing the cam-block turned over and taken in the direction of arrow 4 on Fig. 1.

The cam-block illustrated in said drawings 20 consists of a metallic mass consisting of two integral parts A and A', forming approximately a right angle with each other, having an aperture a extending therethrough near the apex of the angle formed thereby. Said 25 parts are unequal and irregular, the part A' being relatively thin and irregular and the part A being thick and rounded at the end and of greater mass than the part A'. The apex of the angle formed by said parts is 30 rounded. The opposite sides of said cam-block through which said aperture a opens are approximately plane and approximately parallel. On one of said approximately 35 parallel side surfaces is a raised portion integral with the part A and having on one side thereof teeth or ratchets a' a'. The outer end and the edge of said raised portion opposite said teeth or ratchets are rounded, as shown in Figs. 1 and 4. The back portion of 40 the part of said cam-block (indicated by A) is approximately plane and parallel with the axis of the aperture a. The back of the part

(indicated by A') curves inwardly to form the cam-surface oblique to the axis of said aperture, as indicated by a² in Figs. 3 and 4, and terminates in ridges or projections a³ a⁴ on each side of said part, and the end of said part tapers to a rounded obtuse point, while the end of the part A on the side opposite that provided with the teeth or ratchets a' a' is 45 relatively thick and rounded longitudinally, as shown in Figs. 2 and 3. The surface laterally thereof curves slightly inward to the opposite side and forms a part of a continuous cam-surface on the inner side of the cam-block extending from the end of the part A to the end of the part A', as shown in Figs. 2 and 3.

The essential feature of my design is a cam-block consisting of an integral mass 60 composed of two parts, forming approximately right angles with each other and having an aperture extending through the mass adjacent to the apex of said angle, one of the parts of said mass being thick and of greater 65 mass than the other, which is relatively thin and terminates in a rounded point, a continuous cam-surface on the inner side of said block extending from the end of one of said parts to the end of the other and terminating 70 on the rear side of one of said parts, and teeth or projections on one side of the said part A.

Having described my design, what I claim as new, and desire to secure by Letters Patent, is—

A design for the cam-block for car-couplers, substantially as shown and described.

In witness whereof I have hereunto subscribed my name in the presence of two subscribing witnesses.

PHILLIP HIEN.
